FOLDING WINDOW SHADE

David Jackson Spradling, St. Louis, Mo.

Application March 15, 1940, Serial No. 324,195

4 Claims. (Cl. 156—17)

This invention relates to a folding window shade of Venetian type, the general object of the invention being to so construct and arrange the parts of the shade that ropes, pulleys and tape are eliminated and the shade is contracted or expanded by manipulation of the bottom bar and the slats may be easily removed for cleaning purposes without dismantling the entire shade.

Another object of the invention is to so form and arrange the parts that when the shade is in raised position the slats are spaced the same distance apart, thus eliminating the unsightly bundle of slats across the window as in the Venetian shade now in use.

This invention also consists in certain other features of construction and in the combination and arrangement of the several parts to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which—

Figure 1 is a front view of a window showing the improved shade in use therein.

Figure 2 is an end view of the shade arrangement.

Figure 3 is a section on the line 3—3 of Figure 2.

Figure 4 is a view with some of the parts separated of an assembly for supporting one end of a slat.

Figure 5 is an end view of a slat.

Figure 6 is a view of a supporting clip for the bottom bar.

Figure 7 is a view of one end portion of the metal strips assembly.

Figure 8 is a fragmentary view with the parts separated of the supporting means for the bottom bar.

Figure 9 is a view of the supporting clip and its links for the top bar.

In these views the numeral 1 indicates the top or tilting bar of the device and the numeral 2 indicates a pair of brackets for supporting this bar from a window frame, as shown in Figure 1. Each bracket is formed with a top portion 3 for connecting with the top part of the window frame and with a side part which contacts the inner face of a side member of the frame. This latter part of each bracket is connected to an end of the bar 1 by a screw 4 which passes into the center of the end of the bar so that the bar is

supported for rocking movement by these screws. Also each depending part of the brackets is formed with an annular row of depressions 5 which opens out on the bar side of the bracket and each end of the bar is formed with recesses 5 for receiving the spring detents 6 for engaging a pair of the recesses, these detents engaging the recesses holding the bar 1 in adjusted position to which it has been tilted or in a horizontal position. Clips 7 are attached to the bar 1, each clip passing over the upper face of the bar with its ends curving downwardly over the edges of the bar and each end of the clip forms a hinge 8 for a threaded stud 9, see Figure 9. Each stud passes through holes in the upper ends of a pair 10 of links 10 with a nut 11 threaded on the stud for holding the links to the stud. Of course, the links can turn on the stud and the stud with the links can be rocked by the hinge connection with the clip 7. The lower end of one link of 20 each pair is pivotally connected to an end of a metal strip 12, as shown at 13 and the lower end of the other link of the pair is pivotally connected as shown at 14 with an end of a second metal strip 15, see Figure 7. Each pivotal connection 13 and 14 is also a hinged one as shown at 16, the hinge being similar to that shown in Figure 9.

As will be seen from Figures 1 and 7 the downwardly and outwardly extending links of one 30 clip 7 are connected with one end of the upper strip 12 while the outwardly and downwardly extending links of the other clip 7 is connected to an end of the lower strip 15, the inwardly extending links of the first clip 7 being connected 35 to the end of the lower strip 15 and the inwardly extending links of the other clip 7 being connected to the end of the strip 12.

Each slat 17 is formed with notches 18 in its side edges adjacent the ends thereof and each slat rests on an elongated flat bar 19 which has tongues 20 struck therefrom to engage the notches 18, there being one of these bars 19 connected to each end of the slat 17 and the tongues engaging the notches detachably hold the slats 45 to the bars 19. The head of a threaded stud 21 is hinged to each end of each bar 19 as shown at 22 and each stud passes through a washer 23, the central portion of a pair of long links 24 and the eye of a spring 25 which has its ends 50 engaging holes 26 in the links 24, a nut 27 holding the parts together. The springs 25 should be of a strength to counter-balance the weight of the parts of the shade when the parts are assembled. The upper ends of the top links 24 are 55

connected with the pivotal points 13 and 14 of the links 10 while the lower ends of these links 24 are connected to similar links 24 of the slats 17 with the lower ends of the links 24 of the 5 lowermost slat connected to the links 28 which are connected to the bottom bar 29 which has the clips 30 connected therewith, these clips 30, as shown in Figures 6 and 8 having their ends turned upwardly to fit over the edges of the bar 10 29 and they have the threaded studs 31 hinged thereto as shown at 32 with these studs passing through the concavo-convex heads 33 at the lower ends of the links 28 with a small spring 34 on the outer end of each stud 31 and a nut 15 35 threaded to the stud for holding the spring under tension and the heads of the links 28 on the stud. These heads are roughened as shown at 36 to prevent too free movement of the links.

As will be seen by tilting the bar 1 in a horizontal position to one side or the other the slats will be adjusted to a similar position and the parts will be held in this position by the detents 6 engaging recesses or depressions 5 in the brackets 2. By pushing the bar 29 upwardly the slats will 20 be moved toward each other to open the blind and the springs 34 and heads 33 of the links 28 will frictionally hold the parts in adjusted position. Of course, when the bar 29 is pulled downwardly the slats will move apart. The strips 12 and 15 25 will coordinate and equalize the movement of the parts.

As before stated it will be seen that all tape, cord and cables or pulleys are eliminated and the slats can be easily removed for cleaning or repair 30 purposes and replacement.

When the shade is raised or lowered the two sets of links 10 which connect plates 12 with the clips 7 and extend to the right move in one direction while the links which connect the clips with the lower bar 15 and extend to the left move in 40 an opposite direction. Thus these strips and links equalize the movement of the parts so that the slats will remain even in all positions on the shade.

45 It is thought from the foregoing description that the advantages and novel features of the invention will be readily apparent.

It is to be understood that changes may be made in the construction and in the combination 50 and arrangement of the several parts provided that such changes fall within the scope of the appended claims.

Having described the invention, what is claimed as new is:

55 1. A shade of the class described comprising a top bar, a plurality of slats, clips connected with the slats, toggle levers hingedly connected with the ends of said clips and pivotally connected together, levers connecting the top of the

toggle levers with the top bar, a bottom bar, links connecting the bottom bar with the lower ends of the lowermost toggle levers and frictional means for holding the parts in adjusted position when they are moved by upward or 5 downward movement of the bottom bar.

2. A shade of the class described comprising a plurality of slats, cross bars on which the slats are seated, tongues for removably holding the slats to the cross bars, a plurality of toggle levers 10 arranged in pairs, means for pivotally and hingedly connecting a pair of toggle levers to each end of each cross bar, a top bar, clips carried thereby, links pivotally connecting the clips of the top bar to the upper ends of the toggle 15 levers of the top slat, a bottom bar, clips thereon, pairs of links pivotally and hingedly connected to each end of each last-mentioned clip, friction means for retarding pivotal movement of the last-mentioned links, the upper ends of said 20 links being connected pivotally with the lower ends of the toggle levers of the lower slats.

3. A shade of the class described comprising a plurality of slats, cross bars on which the slats are seated, tongues for removably holding the 25 slats to the cross bars, a plurality of toggle levers arranged in pairs, means for pivotally and hingedly connecting a pair of toggle levers to each end of each cross bar, a top bar, clips carried thereby, links pivotally connecting the clips of the top bar to the upper ends of the toggle 30 levers of the top slat, a bottom bar, clips thereon, pairs of links pivotally and hingedly connected to each end of each last-mentioned clip, friction means for retarding pivotal movement of the last-mentioned links, the upper end of said links 35 being connected pivotally with the lower ends of the toggle levers of the lower slat, brackets for connecting with the window frame and to which the ends of the top bar are pivoted for 40 rocking movement of the bar, means for holding the top in adjusted position.

4. A shade of the class described comprising a plurality of slats, cross bars connected with the slat, a plurality of toggle levers arranged in pairs, 45 means for pivotally and hingedly connecting a pair of toggle levers to each end of each cross bar, a top bar, clips carried thereby, links pivotally connecting the clips of the top bar to the upper ends of the toggle levers of the top slat, 50 a bottom bar, clips thereon, pairs of links pivotally and hingedly connected to each end of each last-mentioned clip, friction means for retarding pivotal movement of the last-mentioned links, the upper end of each link being connected pivotally with the lower ends of the toggle levers of the lower slat, and metal strips to which the 55 links of the top bar are pivoted and hinged.

DAVID JACKSON SPRADLING.
